ELECTRIC MEMORY LATCH DEVICE FOR PIANO HAVING ELECTRIC CHORD AND RUN PLAYING MECHANISM

Lee L. Von Gunten, Kenmore, N.Y., assignor to Aurora Corporation of Illinois, Buffalo, N.Y., a corporation of Illinois

Filed Feb. 3, 1961, Ser. No. 87,026
16 Claims. (Cl. 84—245)

The present invention relates to improvements in pianos, and more particularly to new and improved electric memory latch means for a piano having electric chord and run playing means.

This application is a continuation in part of my co-pending application Serial No. 794,902, filed February 24, 1959, and entitled Piano Having Electric Playing Means Therefor.

As disclosed in my aforesaid co-pending application, the improved piano was provided with electric chord and run playing means which incorporated means in the form of a multi-contact sostenuto switch for sustaining or holding a chord played in the control octave of the piano, while enabling the playing of run or arpeggio keys in several octaves, in harmony with the chord keys. As a consequence, the person playing the piano could have both hands free for playing runs in harmony with the held chord. However, the sostenuto switch held the chord keys down during the playing of the runs, with two undesirable effects.

First, the runs were limited to that portion of the piano keyboard above the control octave, and could not be extended down into the richer and more mellow section used as the control octave, because the chord keys in the control octave being held down, could not be sounded again as part of the run. Secondly, the necessity of holding the chord made it difficult for the operator to maintain the rhythm, because the left hand music was virtually at a standstill while the run was being played.

Accordingly, it is a primary object of this invention to provide new and improved electric memory latch means which not only completely eliminates the sostenuto switch formerly required, but also remembers the chord played in the control octave after the chord keys have been released, and enables or makes available any desired number of run playing keys both in harmony with and including the aforesaid chord keys, thereby making it possible to extend the runs down as far as desired into the deeper section of the keyboard and to permit the tempo of the left hand to keep moving steadily, even though a run is in progress.

Another object is to provide such electric memory latch means which may be actuated by the conventional piano sustaining pedal (sometimes called the damper pedal or loud pedal), thereby making the action of the inventive means responsive to conventional piano playing practices with no unusual effort or skill being required on the part of the player, as it is common practice both to hold the sustaining pedal when playing an arpeggio and to release such pedal momentarily when changing chords.

Still another object is to provide such memory latch means which might also be actuated by alternate means independently of the sustaining pedal, in order to permit playing of chromatic scales with the piano dampers on.

A further object is to provide such memory latch means which (1) is adjustable and thereby readily adapted for use with any piano, regardless of the spacing between the various groups of keys which varies with each manufacturer; (2) is simple, yet rugged in construction and capable of repeated usage over long periods of time, and (3) is most effective and efficient in operation.

2

Other objects and advantages of the invention will become apparent upon consideration of the following detailed description and accompanying drawings, wherein:

FIG. 1 is a top plan view of a modern upright spinet piano incorporating an electric chord and run playing mechanism located at the front ends of the keys, and with a portion of the keyboard cover being broken away to illustrate the spacing between groups of keys at their rear ends and a preferred embodiment of the inventive memory latch means associated with such keys;

FIG. 2 is a front elevational view of the piano illustrated in FIG. 1;

FIG. 3 is an enlargement of the broken away portion of FIG. 1 to better illustrate the key spacing and the preferred embodiment of the inventive memory latch means;

FIG. 4 is an enlarged side elevational view illustrating a portion of the keyboard underlying a key in the inoperative or undepressed position, a normally open switch and the inventive memory latch means of FIG. 3 including a solenoid actuated latch finger, all arranged above the key, a preferred type of piano action associated with such key, and a preferred arrangement of key actuating solenoids and their mounting means disposed below the aforesaid piano action;

FIG. 5 is a fragmentary view similar to FIG. 4, but on a slightly larger scale, with the key actuating solenoids and piano action being omitted, and illustrating the key in undepressed or inoperative position, the latch finger moved toward latching position after being energized by the solenoid, but being held by the open switch prior to depression or operation of the piano keys;

FIG. 6 is a fragmentary view similar to FIG. 5, but illustrating the piano key in operative or depressed position closing and elevating the lower contact of the switch to permit the latching finger to move to its latching position;

FIG. 7 is a fragmentary view similar to FIG. 6 following release of the piano key and illustrating the latching finger in latching position to hold the switch in closed position;

FIG. 8 is an enlarged sectional view taken on line 8—8 of FIG. 3 and illustrating the construction of the latching finger and clamping bar;

FIG. 9 is an enlarged fragmentary rear view of the clamping bar and a plurality of latching fingers depending therefrom, viewed from the right of FIG. 8 or the top of FIG. 3, and

FIG. 10 is a schematic view of a circuit diagram including the electric chord and run playing mechanism and the memory latch means.

Referring to the drawings, and particularly FIGS. 1 and 2, a typical modern upright spinet type piano is illustrated therein and includes a cabinet or casing generally indicated at 20. This casing includes the usual cover 21 for enclosing the various piano actions and strings struck thereby (not shown), an upper front panel 22, a lower front panel 23 and a pair of cheeks 24 extending forwardly from each end of the cabinet. These cheeks 24 are supported at their front ends by means of the usual legs 25, and such cheeks are spanned by the usual keyboard 26 composed of eighty-eight keys including the black keys 27 and the white keys 28. A cover 30 is also provided for protecting the rear ends of the keys, and as shown in FIG. 1, this cover is partially broken away to illustrate portions of the inventive memory latch means to be described below.

The piano is also provided with the usual music stand 31 supported on the rear end of keyboard cover 30, and at its lower end, the lower front panel 23 of the piano is recessed to provide for the usual soft pedal 32 on the left,

middle pedal 33 and sustaining or damper pedal 34 on the right. As will be explained below, the damper pedal 34, or alternatively, the middle pedal 33 has an important function in the operation of the inventive memory latch means.

Continuing with FIGS. 1 and 2, a special housing 35 is provided at the front end of the keyboard 26 for an electric chord playing means or control unit generally indicated at 36, such means including two rows each of twelve bass note playing buttons or switches 37 and four rows each of twelve chord playing buttons or switches 38. Housing 35 also contains an electric run playing means generally indicated at 40 and including any desired number of run playing switches or keys 41. Housing 35 is also preferably provided with a combination on-off and volume control switch of the rheostat type 42, and also a pilot light 43 for the convenience of the person playing the piano.

Basically, the chord and run playing means referred to herein are the same as those described and claimed in my aforesaid application Serial No. 794,902 to which reference may be made for a more detailed description of such means.

Referring to FIG. 4, there is illustrated therein a typical key and its operative association with a conventional piano action. In addition, a suitable solenoid mounting means and solenoid means for electrically actuating the action are shown in FIG. 4, together with a preferred embodiment of the inventive memory latch means.

The bed frame for supporting various keys of the keyboard is generally indicated at 44, and each key such as 27 or 28 is pivotally mounted on such bed frame by means of a center pin 45 projecting upwardly from a boss 46 on the frame. At its front end, each key is guided by a front pin 47 extending upwardly from another boss 48 on the frame 44. At its rear end, each key rests upon a suitable bed 50 on the frame, and is connected to its corresponding action, generally indicated at 51, by means of a capstan plate 52 secured to the top rear end of the key by a capstan screw 53. The capstan plate 52 is provided with a hollow grommet 54 receiving a sticker screw 55 suitably threaded into the upper end of a sticker or abstract 56, the latter being pivotally connected at its lower end to the front end of the whip 57.

The whip is suitably connected to the hammer 58 of the action, and upon actuation of a key 27 or 28, the sticker 56 causes the corresponding whip 57 to pivot about its rear end in a clockwise direction as viewed in FIG. 4 thereby causing the hammer 58 to move to the right and to strike its corresponding string 60. At the same time, the whip causes the damper mechanism generally indicated at 61 to momentarily move to the off position away from the string for proper sounding of the desired note. The aforescribed structure and operation of the key and action are conventional and well understood by those skilled in the art.

Likewise, if it is desired that the note struck be sustained, the sustaining pedal 34 illustrated in FIG. 2 is depressed and by suitable connection (not shown) to the damper mechanism 61, holds the latter in the off position. This sustaining structure and operation is also conventional, but does play an important part in the operation of the inventive memory latch means described below.

Continuing with FIG. 4, the means for electrically actuating the action 51 will now be described. Such means preferably includes solenoid mounting means generally indicated at 62 and solenoid means generally indicated at 63, energization of the latter causing actuation of the action. This solenoid means and mounting means therefor are preferably of the type disclosed and claimed in my copending application Serial No. 86,916 filed February 3, 1961 now Patent No. 3,126,783 and entitled Solenoid Means and Solenoid Mounting Means for Pianos, and reference to such application may be made for a more detailed description thereof.

The solenoid mounting means 62 preferably includes an upright support panel 64 which extends transversely of the juxtaposed whips 57 of the various actions 51, and mounted on the support panel are a plurality of vertically spaced and generally horizontal lower clamping bars 65. Each such bar is preferably channel shaped in cross section and is provided with a plurality of suitable means such as screws 66 for fastening the bar to the front flat surface of the panel, and these screws are adjustable for varying the generally normal movement of the bar relative to the panel and the clamping action of the bar with respect thereto.

At its upper end, the support panel 64 is provided with a horizontal and elongated shelf 67 extending transversely of the whips 57, such shelf being secured to the front face of panel 64 by any suitable means (not shown). Spaced below the shelf is an elongated upper clamping bar 68 which is arranged for movement generally normal to the shelf and is secured to panel 64 by suitable means such as screws 70, which screws are adjustable for varying the clamping action of the bar 68 with respect to shelf 67. Adjustably interposed between the shelf and the upper clamping bar are a plurality of juxtaposed guide members 71 (only one of which is shown). Each such guide member has its inner end clamped between the bar and shelf and its outer end protruding frontwardly therefrom and arranged longitudinally of and beneath the corresponding whip 57. The shelf 67 is also provided with a cushioning member 72 on its upper surface for supporting the striking portion of the solenoid means to be described below.

There are actually three solenoid means 63 illustrated, and each includes a generally rectangular casing 73 provided at its lower rear end with one or more tongues 74 adjustably interposed between the upper flange of the corresponding lower clamping bar 65 and the support panel 64. Each casing 73 is also preferably provided with a lower guide means 75 at its front end for controlling the movement of a solenoid armature rod. Arranged within each casing is a solenoid coil means generally indicated at 76, and reciprocally mounted within such coil means is a vertically arranged armature 77 to which is connected an armature rod. Actually portions of three armature rods are shown, the longest being indicated at 78a, the one of intermediate length at 78b and the shortest at 78c. These armature rods reciprocate vertically through the corresponding upper and lower guide means 71 and 75, and are severally provided with laterally offset lower end portions 80a, b and c, respectively, which are suitably secured to the various armatures 77, as well as in-turned upper end portions 81a, b and c, respectively (81a only being shown), each of which is provided with a silent striking member 82 resting upon the cushioning member 72.

As described in detail in my aforesaid copending application Serial No. 86,916, the staggered arrangement of the solenoid means in several horizontal rows, including the variation in length of the armature rods, permits the various striking heads 82 to be located in juxtaposition and severally aligned with their respective whips, such as 57. Upon energization of solenoid means 63, the striking member 82 therefor moves upwardly and causes its corresponding whip 57 to pivot in a clockwise direction as viewed in FIG. 4 to actuate the hammer 58 of the action 51, just as when the piano key is actuated, as described above.

As also seen in FIG. 3, which is an enlargement of the broken away portion of FIG. 1, a plurality of normally open horizontal latching switches, severally indicated generally at 83, are arranged above the rear ends of certain of the black and white keys 27 and 28, respectively, longitudinally thereof and in juxtaposition thereto. Each such switch 83 includes an upper contact 84 and a lower contact 85 vertically spaced therebelow, the lower contact 75 being provided at its rear or inner end with an upstand-

ing flange 86 as shown in FIG. 4. The switches may be suitably secured in their desired positions to a generally horizontal and elongated bar 87 by means of screws 88. This bar 87 is arranged to extend transversely of the keys 27, 28, and may be secured to the piano frame 20 in any suitable manner (not shown).

While such switches 83 are normally open, they are closed upon actuation of their corresponding piano keys 27 or 28, and this result is produced by means of a capstan screw 99 projecting upwardly from each key and adapted to forcibly close the contacts 84, 85, as shown in FIG. 6.

Continuing with FIG. 4 and also referring to FIGS. 3, 8 and 9, the memory latch means constituting a preferred embodiment of the invention will now be described. This memory latch means is generally indicated at 91 and includes a horizontally elongated support plate 92 provided with a rearwardly facing flat surface 92a and extending transversely of certain keys 27, 28. At its upper longitudinal edge, the support plate 92 is provided with an elongated pivot bar 93 which is pivotally mounted in suitable blocks or trunnions 94 (only one of which is shown), and which blocks may be secured to the piano frame 20 in any suitable manner (not shown). As so arranged, the support plate 92 pivots about a generally horizontal axis extending transversely of the piano keys thereabove.

As best seen in FIGS. 8 and 9, a plurality of juxtaposed and elongated, resilient latch fingers 95 engage the rear frame surface 92a of support bar 92 and extend generally vertically downwardly therefrom. At its upper end portion each finger 95 is provided with a pair of vertically spaced, lateral ears or flanges 96, and at its lower end the finger terminates in a generally horizontal and forwardly facing flange or latch 97 which, as shown in FIG. 4, is normally arranged opposite to and spaced from the upstanding flange 86 on lower contact 85 of the corresponding switch 83.

The latch fingers 95 are severally secured to the support plate 92 by means of an elongated and generally horizontal clamping bar 98 which is preferably channel shaped in cross section, its lower flange 98a being shorter than its upper flange 98b and spaced from surface 92a of support plate 92. This lower flange 98a is received between the ears 96 of each finger 95, and the clamping action of the bar with respect to support plate 92 is varied by a plurality of suitable means, such as screws 100, which pass through unthreaded holes in the bar between its flanges and into alined threaded holes in the support plate. As will be apparent, by loosening the screws 100, the latch fingers 95 may be readily adjusted transversely of and alined with their respective switches 83. Likewise, the ears 96 serve to properly locate the fingers 95 laterally of the support plate 92, and also permit such transverse adjustment of the fingers, while maintaining their desired location laterally of the support plate, for proper engagement with the switches 83, as will be described more in detail below.

Referring back to FIG. 4, it will be noted that a leaf spring 101 is secured at one end to trunnion 94 and has its other end biased against the support plate 92 for pivoting the latter rearwardly and thereby maintaining the flanges 97 on the lower ends of latching fingers 95 in spaced relation to the upstanding flanges 86 on switches 83. Likewise, an elongated and generally horizontal stop bar or rod 102 is provided for limiting the rearward movement of the various fingers 95, and this bar may be secured to the piano frame 20 in any suitable manner, not shown.

The preferred embodiment of the inventive memory latch means also includes a solenoid, generally indicated at 103, which is suitably supported on the bar 87 and includes a generally horizontal, reciprocal armature 104 having an armature rod 105 pivotally connected at its outer or rear end with the pivotal support plate 92 by means of one or more flanges 106 extending forwardly

therefrom. Circuit means are provided for energizing the solenoid 103 and include a power input line 107 and a ground line 108, the former line including a normally open switch 110, upon closing of which the solenoid 103 is energized.

Actually, switch 110 is preferably closed by depression of the sustaining pedal 34 referred to previously, this being a natural function of the person playing the piano, because it is normal practice to depress the sustaining pedal when the note sounded is desired to be sustained. Alternatively, or in addition, the input line 107 may also be provided with a similar normally open switch 111, indicated in dotted lines in FIG. 4, and if desired, this switch may be located beneath and closed by actuation of the middle pedal 33, illustrated in FIG. 2. This alternative switching arrangement is desirable when playing chromatic scales, which would sound quite dissonant with the dampers off, it being apparent that operation of the sustaining pedal 34 also moves the dampers to the off position.

Referring to FIGS. 4-7 in particular, the operation of the inventive memory latch means will now be described. As seen in FIG. 4, both the piano key 28 and the resilient latch fingers 95 on the pivotal support plate 92 are at rest or deactuated. As illustrated in FIG. 5, the switch 110 or 111 has been closed to energize the solenoid 103, whereby the support plate 92 pivots to the left and causes the latch 97 on each finger 95 to engage or abut against the corresponding upstanding flange 86 on the lower contact 84 of the corresponding switch 83. Thus, it will be apparent that unless the piano key is actuated to close the normally open latch switch 83, closing of switch 110 or 111 will only cause the latch finger 95 to abut against the still open switch.

Referring now to FIG. 6, the piano key 28 has been actuated, whereupon the capstan screw 99 forces the lower contact 85 into engagement with the upper contact 84, thereby closing the switch 83. Since the solenoid 103 has been energized, the latch finger 95 moves underneath the closed switch 83 into operative position. Thus, when the piano key 28 is released, the flange or latch 97 on finger 95 remains in latching engagement with the lower contact 85 and maintains the switch 83 closed.

In effect then, the inventive latching means remembers a certain note or notes which have been played to enable the playing of run notes both in harmony with and including those notes which have been played, while permitting the actuated note playing keys 27, 28 to be released.

Referring now to FIG. 10, the electrical circuitry for the inventive memory latch means, chord playing means and run playing means will be described. This circuitry includes any suitable D.C. power supply generally indicated at 112, a power supply line 113 and a power return or main ground line 114, the input lead 107 for pedal switches 110 and 111 of the inventive memory latch means being connected to supply line 113 and the output lead 108 from latch solenoid 103 being connected to return line 114.

As will be noted, most of the keyboard 26 is illustrated schematically with reference to the various notes, and a portion of the keyboard is designated as a control octave. Actually, this octave includes fifteen notes ranging from D above middle C to C below middle C, inclusive, and a normally open latching switch 83 is provided for each key in this octave.

There are actually twelve parallel individual circuits 115-126 severally connected to the supply line 113 and severally including the various latching switches 83, the switches corresponding to the last three notes C, D flat and D at the lower or left hand end of the control octave merely being added in parallel to the circuits 115, 116 and 117, respectively, which correspond to middle C, D flat and D thereabove. The leads from the three lower

switches are designated at 115', 116' and 117', respectively.

These individual circuits 115-126 severally include the run playing switches 41 severally connected in series with the corresponding latching switches 83, and the circuits are completed by the chord playing solenoids which are designated as 63c, and are twelve in number. In addition, each of the individual circuits 115-126 includes parallel branches having the same numbers followed by the subscripts a-d and such parallel branches severally including additional run playing switches identical to those numbered 41, but severally designated by the subscripts a-d. For example, in tracing the individual circuit corresponding to the key for playing middle C, one would follow the circuit line 115 through normally open latching switch 83 and normally open run switch 41 to the corresponding solenoid 63c. In tracing the parallel branches of this particular circuit, one would follow back from the run switch 41 along circuit line 115, first to branch line 115a and through run playing switch 41b to the corresponding run playing solenoid 63r, the latter being connected to the main ground line 114, next from line 115 through branch line 115b and run switch 41c to the corresponding run solenoid, and finally through branch line 115c and run switch 41d to the corresponding run solenoid.

Likewise, taking the circuit for the key corresponding to the note B immediately below middle C, one would follow line 126 through latching switch 83 and run playing switch 41 to the corresponding chord solenoid 63c. Then tracing the parallel branches, one would backtrack along line 126 from run playing switch 41, first through branch line 126a and run switch 41a to corresponding solenoid 63r, second through branch line 126b, run switch 41b to the corresponding run solenoid, and finally through branch line 126c and run switch 41c to the corresponding run solenoid.

In addition, if one were to trace the individual circuit for the key for playing the note F below middle C, he would trace along individual circuit line 120 through latching switch 83 and run playing switch 41 to the corresponding solenoid 63c. Then, in tracing the parallel branches, he would backtrack along line 120 from run switch 41, first through branch line 120a including run switch 41a to the run solenoid, next through branch line 120b and run switch 41b to its solenoid, third through branch line 120c and run switch 41c to the corresponding solenoid, and finally through branch line 120d and run switch 41d to the corresponding run solenoid 63r.

From the foregoing, it will be apparent that the individual circuits 115-126 are provided with a plurality of parallel branches varying in number, the circuit for note middle C and note B below middle C having three parallel branches while the circuit for note F below middle C has four middle branches. Each branch for each circuit associates the solenoid 63c of that circuit with the run solenoid 63r for the note in a higher octave corresponding to the note in the control octave.

Thus, assume that the note middle C is played in the control octave. Whether this note be played mechanically by depressing a piano key such as 28, manually or by actuating the key and its corresponding action electrically through solenoid means 63c, for example, the corresponding latching switch 83 is closed by such actuation. If either one of the pedal switches 110 or 111 is closed, the corresponding latching finger 95 maintains the switch 83 closed following release or deactuation of the piano key. As a result, the individual circuit 115 is enabled, and upon closing its sequence run playing switch 41 corresponding to the note middle C, as well as run switches 41b, 41c and 41d corresponding to the notes C in successive higher octaves, a run of C notes is played, both including middle C in the control octave as well as the corresponding C notes in the successive higher octaves in harmony therewith.

The same result is obtained if a chord is played in the control octave, as the latching fingers corresponding to the notes of the chord will maintain the latching switches closed and enable those individual circuits for the playing of runs of notes both in harmony with and including the notes of the chords in the control octave. All of this is accomplished following release of the piano keys originally striking the notes in the control octave.

In view of the fact that it is preferred that switch 110 be employed to energize the solenoid 103 of the inventive latching means, this switch 110 is operatively associated with the sustaining pedal 34 to facilitate such playing of runs, because normally when a chord is played, the sustaining pedal is depressed to hold the chord. On the other hand, if a chromatic scale or scales are to be played, the alternative switch 111 could be used by actuating the middle pedal 33, thereby leaving the dampers on to avoid dissonance.

Continuing with FIG. 10, the electrical circuitry also preferably includes the electrical chord playing means or control unit diagrammatically illustrated at 36. For playing chords within the control octave, the chord playing means includes twelve individual circuits 135-146 severally connected to the individual latching circuits 115-126, respectively, each connection being made in series between the corresponding run playing switch 41 and the chord playing solenoid 63c. These individual chord playing circuits are closed by the chord playing button or switches 38, the latter being arranged in four rows, with twelve switches per row, only four switches per row being shown in FIG. 10 for clarity. Thus, upon depression of one of the switches or buttons 38, a predetermined plurality of the individual chord note circuits 135-146 are simultaneously closed to energize the corresponding solenoids 63c, which solenoids, in turn, actuate the corresponding action and sound the desired notes of the chord of the control octave. A more detailed description of this structure and operation is contained in my aforesaid application Serial No. 794,902.

It will be noted that there are only twelve individual chord note circuits 135-146, and thus, when electrically playing chords in the control octave, the notes are limited to the twelve notes beginning with D above middle C to E flat below middle C, inclusive. Likewise, the runs are limited to such twelve notes within the control octave. The reason for having the three additional notes below E flat is to permit one who is manually playing the keys of the control octave to have a greater range, as it is sometimes difficult to limit the manual playing of the chords precisely to the twelve basic notes of the control octave.

While the aforescribed is a preferred embodiment of the invention, it will be apparent that the chord solenoids 63c could be extended to include these three notes at the lower end of the control octave, and that the corresponding run switches 41 could also be supplied to expand the runs to include these three notes. Actually, if desired, the solenoids 63c could be extended over the entire keyboard, as could the latching switches 83 and the run playing switches 41. However, for normal playing of the piano, this is not necessary.

Referring back to the chord playing means 36, it will also be noted that twelve additional individual circuits are provided, and each is numbered 150. These circuits are connected to the so-called bass solenoids 63b associated with the keys for a bass octave, and are closed by the twelve bass switches or buttons 37 in the upper two rows of the chord control unit 36, only four buttons in each row being shown in FIG. 10 for clarity. As described in greater detail in my aforesaid application Serial No. 794,902, these bass note playing buttons or switches 37 facilitate the playing of chromatic scales in the bass octave.

The chord playing means 36 is conveniently connected to the power supply line 113 by means of the lead 151.

From the foregoing, it will be apparent that the inventive memory latch means is useable whether the chords in the control octave are played manually by depressing keys, or electrically by means of the chord playing means 36. Further, it will be apparent that the present invention possesses a definite advantage over the sustaining means employed in my aforesaid application Serial No. 794,902, because the keys in the chord control octave need not remain depressed or actuated while playing the runs, by depressing the juxtaposed run playing switches 41, 41a, 41b, etc. This permits the extension of the runs down as far as desired into the deeper and more mellow section of the keyboard including the control octave itself, and permits the tempo of the left hand to keep moving steadily, even though a run is being played with the right hand.

Furthermore, the employment of the usual sustaining pedal 34 for closing the switch 119 in the latching means circuit follows the normal piano playing technique of sustaining a chord struck, and is a natural function for which no additional training is required on the part of the person playing the piano. In addition, it will be noted that the construction of the memory latch means, particularly the clamping bar 98 and the latching fingers 95, facilitates the adjustment of the latching fingers transversely of and into alignment with the corresponding latching switches 83, regardless of the spacing of the groups of keys, which spacing varies from one piano manufacturer to another. This feature makes the inventive memory latch means truly universal in character, in that it can be readily adapted for use for most any make of piano.

Finally, the locking engagement between the flanges or ears 96 provided on the inner end portions of each latching finger and the lower flange 98a of the clamping bar not only serves to properly locate the latching fingers laterally of the pivotal support plate for proper cooperation with the latching switches 83, but also permits the desired transverse adjustment and alignment of the latching fingers with the latching switches, while maintaining the desired lateral location of the latching fingers.

While the invention has been described and illustrated herein with reference to a single preferred embodiment, it is to be understood that various changes and modifications may be made therein by those skilled in the art without departing from the invention, the scope of which is to be determined by the appended claims.

What is claimed is:

1. In a piano, the combination comprising a plurality of individual note playing means, a plurality of solenoids severally operatively associated with said note playing means for an octave and each of said solenoids when energized being arranged to actuate its companion note playing means, a source of electrical energy, individual circuit means connected to said source and solenoids and including first and second normally open switch means, said first switch means being closed upon actuation of the corresponding note playing means of said octave, said second switch means being selectively closeable manually, and memory latch means selectively operable for maintaining said first switch means closed following actuation and de-actuation of said corresponding note playing means.

2. In a piano, the combination comprising a plurality of individual note playing means, a plurality of solenoids severally operatively associated with said note playing means for more than one octave and each of said solenoids when energized being arranged to actuate its companion note playing means, a source of electrical energy, individual circuit means connected to said source and associating the solenoid for each note playing means of one octave with the solenoid for the corresponding note playing means of another octave and including first and second normally open switch means, said first switch means being closed upon actuation of the corresponding note playing means of said one octave, said second

75

switch means being selectively closeable manually, and memory latch means selectively operable for maintaining said first switch means closed following actuation and de-actuation of said corresponding note playing means of said one octave.

3. In a piano, the combination comprising a plurality of individual note playing means, a plurality of solenoids severally operatively associated with said note playing means for more than one octave and each of said solenoids when energized being arranged to actuate its companion note playing means, a source of electrical energy, individual circuit means connected to said source and associating the solenoid for each note playing means of one octave with the solenoid for the corresponding note playing means of another octave and including first and second normally open switch means arranged in series, said first switch means being closed upon actuation of the corresponding note playing means of said one octave, said second switch means being selectively closeable manually, and memory latch means selectively operable for maintaining said first switch means closed following actuation and de-actuation of said corresponding note playing means of said one octave.

4. In a piano, the combination comprising a plurality of individual note playing means, a plurality of solenoids severally operatively associated with said note playing means for more than one octave and each of said solenoids when energized being arranged to actuate its companion note playing means, a source of electrical energy, individual circuit means connected to said source and associating the solenoid for each note playing means of one octave with the solenoid for the corresponding note playing means of another octave and including first, second and third normally open switch means, said first switch means being closed upon actuation of the corresponding note playing means of said one octave, said second and third switch means being selectively closeable manually, and memory latch means selectively operable for maintaining said first switch means closed following actuation and de-actuation of said corresponding note playing means of said one octave.

5. In a piano, the combination comprising a plurality of individual note playing means, a plurality of solenoids severally operatively associated with said note playing means for more than one octave and each of said solenoids when energized being arranged to actuate its companion note playing means, a source of electrical energy, individual circuit means connected to said source and associating the solenoid for each note playing means of one octave with the solenoid for the corresponding note playing means of another octave and including first, second and third normally open switch means, said first switch means being arranged in series with said second and third switch means and being closed upon actuation of the corresponding note playing means of said one octave, said second and third switch means being selectively closed manually, and memory latch means selectively operable for maintaining said first switch means closed following actuation and de-actuation of said corresponding note playing means of said one octave.

6. In a piano, the combination comprising a plurality of individual note playing means, a plurality of solenoids severally operatively associated with said note playing means for more than one octave and each of said solenoids when energized being arranged to actuate its companion note playing means, a source of electrical energy, individual circuit means connected to said source and associating the solenoid for each note playing means of one octave with the solenoid for the corresponding note playing means of another octave and including first, second and third normally open switch means, said first switch means being closed upon actuation of the corresponding note playing means of said one octave, said second and third switch means being arranged in parallel and being selectively closeable manually, and memory

latch means selectively operable for maintaining said first switch means closed following actuation and de-actuation of said corresponding note playing means of said one octave.

7. In a piano, the combination comprising a plurality of individual note playing means, a plurality of solenoids severally operatively associated with said note playing means for more than one octave and each of said solenoids when energized being arranged to actuate its companion note playing means, a source of electrical energy, individual circuit means connected to said source and associating the solenoid for each note playing means of one octave with the solenoid for the corresponding note playing means of another octave and including first, second and third normally open switch means, said first switch means being arranged in series with said second and third switch means and being closed upon actuation of the corresponding note playing means of said one octave, said second and third switch means being arranged in parallel and being selectively closeable manually, and memory latch means selectively operable for maintaining said first switch means closed following actuation and de-actuation of said corresponding note playing means of said one octave.

8. In a piano, the combination comprising a plurality of individual note playing means, a plurality of solenoids severally operatively associated with said note playing means for more than one octave and each of said solenoids when energized being arranged to actuate its companion note playing means, a source of electrical energy, a plurality of individual circuit means arranged in parallel and severally connected to said source, each individual circuit means associating the solenoid for each note playing means of one octave with the solenoid for the corresponding note playing means of another octave and each including first, second and third normally open switch means, said first switch means being arranged in series with said second and third switch means and being closed upon actuation of the corresponding note playing means of said one octave, said second and third switch means being arranged in parallel and being selectively closeable manually, and memory latch means selectively operable for maintaining each of said first switch means closed following actuation and de-actuation of each of said corresponding note playing means of said one octave.

9. In a piano, the combination comprising a plurality of individual note playing means, a plurality of solenoids severally operatively associated with said note playing means for more than one octave and each of said solenoids when energized being arranged to actuate its companion note playing means, a source of electrical energy, run playing means including a plurality of individual run circuit means arranged in parallel and severally connected to said source, each individual run circuit means associating the solenoid for each note playing means of one octave with the solenoid for the corresponding note playing means of another octave and each including first, second and third normally open switch means, said first switch means being arranged in series with said second and third switch means and being closed upon actuation of the corresponding note playing means of said one octave, said second and third switch means being arranged in parallel and being selectively closeable manually, chord playing means including a plurality of individual circuit means arranged in parallel and severally connected to said source and said individual run circuit means between said second switch means and the solenoids for the corresponding note playing means of said one octave, said chord playing means having a plurality of normally open switch means selectively closeable manually for simultaneously closing a plurality of individual chord circuit means and thereby simultaneously energizing a plurality of the solenoids for actuating the corresponding note playing means of said one octave, and memory latch means selectively operable for maintaining

each of said first switch means closed following actuation and de-actuation of each of said corresponding note playing means of said one octave.

10. In a piano, the combination comprising note playing means, normally open switch means closed upon actuation of said note playing means, and memory latch means for maintaining said switch means closed following actuation and de-actuation of said note playing means and comprising finger means moveable into latching engagement with said switch means when closed, solenoid means energizable for so moving said finger means, a source of electrical energy and circuit means connected to said source and including normally open switch means selectively closeable for energizing said solenoid means.

11. In a piano, the combination comprising a plurality of juxtaposed individual note playing means, a plurality of juxtaposed normally open switch means severally operatively associated with said note playing means and closed upon actuation of the corresponding ones of said note playing means, and memory latch means for severally maintaining said switch means closed following actuation and de-actuation of said corresponding note playing means and comprising moveable support means, a plurality of juxtaposed finger means engaging said support means, bar means clamping said finger means to said support means, solenoid means operatively associated with said support means and energizable for moving said finger means severally into latching engagement with the corresponding ones of said switch means when closed, a source of electrical energy and circuit means connected to said source and including normally open switch means selectively closeable for energizing said solenoid means.

12. In a piano, the combination comprising a key, a normally open switch closed upon actuation of said key, and memory latch means for maintaining said switch closed following actuation and de-actuation of said key and comprising a movable support having a flat surface, a clamping bar opposing said flat surface, a finger adjustably interposed between said flat surface and clamping bar, a solenoid operatively associated with said support and energizable for moving said finger into latching engagement with said switch when closed, a source of electrical energy and a circuit connected to said source and including a normally open switch selectively closeable for energizing said solenoid.

13. In a piano, the combination comprising a plurality of juxtaposed keys, a plurality of juxtaposed normally open switches severally operatively associated with said keys and each closed upon actuation of the corresponding one of said keys, and memory latch means for severally maintaining said switches closed following actuation and de-actuation of said corresponding keys and comprising a movable support having a flat surface and arranged transversely of said switches, a clamping bar arranged transversely of said switches and opposing said flat surface, means fastening said clamping bar to said support and being adjustable to vary the clamping action of said bar with respect to said support, a plurality of juxtaposed fingers each having one end clamped between said flat surface and clamping bar and its other end protruding laterally outwardly therefrom opposite the corresponding one of said switches, a solenoid operatively associated with said support and energizable for moving said fingers severally into latching engagement with said switches when closed, a source of electrical energy and a circuit connected to said source and including a normally open switch selectively closeable for energizing said solenoid.

14. In a piano, the combination comprising a key, a normally open switch arranged longitudinally of and closed by said key upon actuation thereof, and memory latch means for maintaining said switch closed following actuation and de-actuation of said key and comprising a pivotally movable support having a flat surface and being arranged transversely of said key and switch, a clamping

bar of generally channel shaped cross-section arranged transversely of said key and switch and having its flanges opposing said flat surface, means fastening said bar to said support and being adjustable to vary the clamping action of said bar with respect to said flat surface, a resilient finger having one end clamped between said flat surface and bar and its other end protruding laterally outwardly therefrom opposite and normally spaced from said switch, a solenoid including a reciprocal armature rod connected to said support and being energizable for pivoting said finger toward and into latching engagement with said switch when closed, resilient means operatively associated with said support for maintaining said finger spaced from said switch when said solenoid is deenergized, a source of electrical energy and a circuit connected to said source and including a normally open switch selectively closeable for energizing said solenoid.

15. In a piano, the combination comprising a plurality of generally horizontal keys arranged in juxtaposition, a plurality of normally open and generally horizontal switches severally operatively associated with said keys and arranged in juxtaposition longitudinally above the rear ends of the corresponding ones of said keys and being severally closed by said corresponding keys upon actuation thereof, each switch including a vertically spaced pair of contacts with the lower contact terminating at one end in an upstanding flange and being moved upwardly into engagement with the upper contact by its corresponding key, and memory latch means for severally maintaining said switches closed following actuation and de-actuation of said keys and comprising an elongated support having a generally vertical flat surface and being arranged for pivotal movement about a generally horizontal longitudinal axis extending transversely above said switches, an elongated and generally horizontal clamping bar of generally channel shaped cross-section arranged transversely above said switches and having its flanges opposing said flat surface with its lower flange being narrower than its upper flange and spaced from said flat surface, a plurality of means severally extending through said bar between said flanges and into said support for fastening

40

said bar thereto and being adjustable to vary the clamping action of said bar with respect to said flat surface, a plurality of elongated and generally vertical resilient fingers arranged in juxtaposition and each having its inner end clamped between said lower flange of said bar and flat surface and its outer end protruding downwardly therefrom and terminating in a generally horizontal flange opposing and normally spaced from the corresponding upstanding lower contact flange, a solenoid including a reciprocal armature rod connected to said support and being energizable for pivoting said fingers toward said switches, whereupon said horizontal finger flanges severally abut said upstanding lower contact flanges when said switches are open and severally move beneath said upstanding contact flanges into latching engagement with said lower contacts when said switches are closed, resilient means operatively associated with said support for maintaining said fingers spaced from said switches when said solenoid is deenergized, a source of electrical energy and a circuit connected to said source and including a normally open switch selectively closeable for energizing said solenoid.

16. The combination of claim 15 wherein said inner end of each latch finger is provided with a vertically spaced pair of ears receiving said lower flange of said clamping bar, whereby said fingers may be moved transversely of and severally aligned with said switches upon adjustment of said fastening means while maintaining the location of said fingers laterally of said support.
